UNITED STATES PATENT OFFICE.

KARL MATHEUS AND EDWARD THOMAS HENDEE, OF CHICAGO, ILLINOIS.

PISTON.

No 882,572.

Specification of Letters Patent. Patented March 24, 1908.

Application filed July 22, 1907. Serial No. 384,867.

To all whom it may concern:

Be it known that we, KARL MATHEUS and EDWARD THOMAS HENDEE, both citizens of the United States, and residing at Chicago, in the county of Cook and State of Illinois, have invented a new and useful Improvement in Pistons, of which the following is a complete specification.

This invention relates to improvements in pistons and more particularly to a piston adapted to change the position of its wearing surface with respect to the cylinder.

Heretofore reciprocating pistons have been so constructed that any given point on the wearing surface thereof travels in a straight line longitudinally of the cylinder and consequently all of its wear at that point is along that line.

The object of this invention is to provide a piston in which the wearing surface thereof changes its position with respect to the cylinder, or in other words, to provide a piston in which any given point on its wearing surface travels in an irregular line longitudinally of the cylinder instead of in a straight line.

It is a further object of the invention to provide a piston having a revolvable wearing surface adapted to be revolved by the pressure of the motive fluid during its operation.

It is also an object of the invention to provide a very cheap and simple construction adapted to greatly lengthen the life of both the cylinder and the piston.

The invention consists of the matters hereinafter described in the specification and more fully pointed out and defined in the appended claims.

In the drawings: Figure 1 is a view partly in section and partly in side elevation of a piston embodying my invention. Fig. 2 is an end elevation thereof. Fig. 3 is a section of the following ring. Fig. 4 is an outer face view of the same. Fig. 5 is a side elevation of one of the rollers. Fig. 6 is a fragmentary section of the bull ring. Fig. 7 is a fragmentary end view thereof. Fig. 8 is a fragmentary section of the spider. Fig. 9 is a fragmentary end view of the piston with the piston rod removed.

As shown in said drawings: 1 indicates the tapered end of a piston rod of a reciprocating piston, and rigidly engaged thereon by means of a nut 1' is a disk 2 of any preferred construction and material, preferably of cast metal, but which as shown is cored to form a

spider and is of less diameter than the diameter of the cylinder in which it is to be used. At one end of said spider is provided a peripheral flange 2', and at the other end is a peripheral groove or recess providing a shoulder 3 which is screw threaded, and a shoulder 4, which is provided in its periphery with a plurality of recesses 4'. A roller 5 is journaled in each of said recesses upon a shaft 5', engaged in the walls of the recess, and each of said rollers projects slightly beyond the periphery of the shoulder 4, as shown more clearly in Figs. 1 and 8.

Having threaded engagement on the shoulder 3 is a locking ring 6 which is adapted to be screwed in against the shoulder 4 and locked in place by a tap screw 6' having threaded engagement between the shoulder 3 and said ring, as shown in Figs. 1 and 2. Said ring 6 is provided with a peripheral flange 7, corresponding with the flange 2' of the spider and is also provided with a plurality of peripheral recesses 7', corresponding with the recesses 4' in the shoulder 4. Journaled in said recesses 7' on shafts 8 are the rollers 8' which also project slightly beyond the periphery of the ring.

Within the seat formed between the flanges 2' and 7, and bearing upon the rollers 5 and 8', is the ring 9, which I have termed the bull ring and which fits closely between said flanges and is provided with laterally projecting flanges 9', which project over the flanges 2' and 7. Said ring 9 is provided in its outer surface with grooves in which are seated the packing-rings 10 of any desired construction, preferably of soft metal, and which are held in place by tap screws 10', as shown in Fig. 1. In one side of said bull ring 9 is provided a plurality of recesses or ports 11 which, as shown more clearly in dotted lines in Fig. 1, have their end walls inclining towards each other and one of which is more abrupt than the other, so that steam exerts 100 greater force against it and causes the ring to rotate.

The operation is as follows: In assembling the device the bull ring 9 is inserted over the shoulder 4 onto the flange 2' and then the locking ring is screwed in place by engaging any suitable instrument in the holes 12 in the outer face thereof. When said ring has been inserted to its limit the tap screw 6' is inserted in its aperture and the ring is held 110 thereby firmly in position. Inasmuch as the bull ring engages the rollers it is obvious

2
that it is free to rotate thereon, thereby providing a rotative wearing surface for the piston. When steam, gas, air, liquid or any other pressure is admitted to the cylinder it enters the ports or recesses 11 in the bull ring and owing to their form causes the ring to rotate slightly in the cylinder during each impulse of the piston. Obviously with a piston whose wearing surface is continuously shifting its line of travel with respect to the cylinder, the wear will be very evenly distributed and obviously many details of construction may be varied without departing from the principles of my invention.

15 We claim as our invention:

1. In a device of the class described the combination with a disk of means affording a rotative wearing surface on its periphery and means adapting said surface to be rotated by fluid pressure.

2. In a device of the class described the combination with a disk of a peripheral ring rotatively engaged thereon and means for rotating the same during the operation of 20 the piston.

25 3. In a reciprocating piston, a bull ring providing the wearing surface therefor and roller bearings for said ring.

4. In a device of the class described the combination with a spider of an automatically rotating ring thereon and means for securing said ring in place.

30 5. In a device of the class described the combination with a spider of roller bearings thereon and a ring mounted on said bearings 35 and affording a wearing surface.

6. In a device of the class described the combination with a disk of a peripheral ring fitting thereon, anti-friction bearings between said disk and ring and means for 40 securing said ring in position.

7. In a device of the class described the combination with a piston rod of a spider thereon, a rotative ring on the periphery of 45 said spider, a locking ring adapted to be engaged on the spider and hold the rotative ring in place and anti-friction bearings for said rotative ring.

8. In a device of the class described the 50 combination with a spider of roller bearings on its periphery, a locking ring adapted to be engaged on said spider, roller bearings thereon in alinement with the bearings on

the spider and a ring rotatively engaged on said bearings.

9. In a device of the class described the combination with a spider having a peripheral flange thereon, of a locking ring having a peripheral flange thereon, anti-friction bearings on said spider and ring between said flanges and a ring rotatively engaged on said 60 bearings.

10. In a piston, the combination with a disk having a peripheral race thereon, of anti-friction bearings in said race a ring mounted 65 on said bearings and having recesses in one side thereof, and packing rings in the circumference of said ring.

11. In a device of the class described the combination with a spider of a rotative ring 70 carried on its periphery and having steam ports in one side thereof.

12. In a device of the class described the combination with a piston head, having a peripheral seat therein, of anti-friction bearings in said seat and a bull ring mounted on 75 said bearings and adapted to revolve during the operation of the piston.

13. The combination with a piston head having a flange and a plurality of recesses at 80 its periphery, of roller bearings journaled in said recesses, a locking ring adapted for threaded engagement with said piston head and provided with a flange and recesses at 85 its periphery, roller bearings in the recesses of said ring, and a bull ring mounted on said roller bearings between said flanges.

14. In a device of the class described the combination with a spider providing a piston head, of a locking ring having threaded 90 engagement with said spider, means for locking said ring in place, roller bearings in the periphery of said ring and spider, and a bull ring mounted thereon and provided in its side with a plurality of abutment recesses in 95 which fluid pressure acts to rotate the bull ring.

In testimony whereof we have hereunto subscribed our names in the presence of two witnesses.

KARL MATHEUS.
EDWARD THOMAS HENDEE.
